UNITED STATES PATENT OFFICE.

CHARLES MELCHIORI, OF STAMBAUGH, MICHIGAN.

FUNNEL.

1,237,800.

Specification of Letters Patent. Patented Aug. 21, 1917.

Application filed October 22, 1915. Serial No. 57,320.

To all whom it may concern:

Be it known that I, CHARLES MELCHIORI, a citizen of the United States, residing at Stambaugh, in the county of Iron and State 5 of Michigan, have invented certain new and useful Improvements in Funnels; and I do hereby declare the following to be a full, clear, and exact description of the invention, such as will enable others skilled in the art 10 to which it appertains to make and use the same.

This invention relates to new and useful improvements in funnels and the principal object of the invention is to provide a funnel 15 having a vent to carry off the compressed air formed in the top of a vessel when the same is being filled by a funnel.

Another object of the invention is to prevent the wasting of the liquid which is being poured into the vessel around the spout and to provide a funnel which will fit tightly therearound and yet will allow the air within 20 the upper part of the vessel to escape.

A further object of the invention is to 25 provide a funnel having a valve for closing the lower end of the stem thereof, thus allowing the user to remove the funnel when the vessel being filled has reached its full capacity without danger of wasting any of 30 the liquid.

Still another object of the invention is to provide a novel means for mounting the lever controlling the operation of the valve.

With these and other objects in view, the 35 invention consists in the novel combination and arrangement of parts which will be fully set forth in the following specification and accompanying drawings, in which:

Figure 1 is a vertical sectional view through 40 a funnel constructed in accordance with this invention.

Fig. 2 is a horizontal sectional view on the line 2—2 of Fig. 1, and

Fig. 3 is a fragmentary detail side elevation 45 of the lever for controlling the valve.

Referring to the drawings, the numeral 1 designates the main body of the funnel comprising the frusto-conical hollow member having formed at its reduced end, the 50 stem 2. The lower end of this stem terminates in a valve seat 3, formed by an out-turned flange and the upper end of the body 1 is provided with a bead 4. A suitable handle 5 is secured to the body for the convenient handling of the device and surrounding 55 the stem 2 at a point a little above the

valve seat 3 is a rubber bushing 6 formed of a relatively soft rubber and provided at its upper end with the bead 7. This bushing tapers as shown to conform to the shape 60 of the stem and is adapted to prevent the escape of the liquid between the stem and the filling spout of the vessel in which the device is used.

Formed at the extreme lower end of the 65 tube or stem 2 is an opening 8 in which the lower end of the vent tube 9 is secured. This vent tube extends upwardly and is bent angularly as at 10 to conform to the shape 70 of the body 1 and is secured at 11 to the body near its upper edge.

In order to enable the user to move the funnel without wasting any of the contents there is secured to the body 1 near its upper edge at a point diametrically opposite the 75 point 11 at which the tube 10 is secured a suitable U-shaped staple 12. This staple 12 projects inwardly and forms a bearing for the handle by which the valve is controlled which comprises the loop 13 one end of 80 which is extended as at 14 and this extended portion is bent back upon itself at 15 and the bent back portion is extended as at 16 and forms a loop 17. The extended portions 14 and 16 together with the bight portion 15 85 forms a handle or thumb piece which projects beyond the side wall of the funnel and the loops 13 and 17 form pivots on the bight portion of the staple 12 for supporting the thumb piece. The end of the loop 12 opposite the portion 16 is extended to form a lever 18 which terminates in an eye 19 and extending through the eye 19 is the bight portion of an eye 20 formed at the upper end of the rod 21, the lower end of which 90 is screw threaded as at 22 to receive the nut 23 which limits the downward movement of the valve 24 consisting of an oval body 25 of rubber or a similar relatively soft material having a central opening formed axially therethrough for the reception of the link or stem 21. It will thus be seen that the valve being of such a shape will readily seat against the valve seat 3 to close 95 the lower end of the stem 2.

It will be apparent from the foregoing that in use, the funnel is placed in the vessel in the usual manner, and the bushing 6 will engage the side walls of the filling spout. The user then pours the liquid into the funnel and as the vessel fills, it will be noted that the air rising to the top of the vessel 110

will pass out through the vent tube 9, thereby avoiding the possibility of wasting the liquid around the point where the funnel extends into the filling spout. Should the vessel become full so that a certain amount of liquid will be left standing in the funnel, the user will then press upon the thumb piece, thus moving the arm 18 upwardly and exerting pull on the link 21 so that the valve 10 will be drawn into engagement with the seat 3 and the funnel may then be lifted from the vessel without danger of spilling or wasting any of its contents.

While in the foregoing there has been shown and described the preferred embodiment of this invention, it is to be understood that such changes may be made in the combination and arrangement of parts as will fall within the spirit and scope of the appended claim.

What is claimed is:

A funnel comprising a body, a stem formed on the body and having its end flared

to form a valve seat, a staple secured to the inner face of the body adjacent its upper end, a wire having one end looped about the staple and being bent upon itself in spaced relation and disposed over the body and looped about the staple to form a handle, one end of said wire after forming one of the loops being extended forwardly and bent to form an arm, said arm having its free end disposed over the stem and bent to form an eye, a rod pivoted to said eye extending through the stem and screw threaded, an oval shaped valve located on the rod and adapted to move into engagement with the valve seat by said handle, and a nut threaded to the rod for adjustably supporting the valve thereon.

In testimony whereof I affix my signature in presence of two witnesses.

CHARLES MELCHIORI.
